LASTING MACHINE

Bernhardt Jorgensen, Beverly, Mass., assignor to
United Shoe Machinery Corporation, Paterson,
N. J., a corporation of New Jersey

Application August 19, 1932, Serial No. 629,514

53 Claims. (Cl. 12—7)

This invention relates to machines for manufacturing shoes or other footwear and in some aspects especially to machines for making footwear in which the lasted upper is secured to the sole by cement or other adhesive, the term "sole" being commonly used herein to include the insole of some kinds of shoes. It is herein shown as embodied in a machine for carrying out certain steps in the manufacture of gaiters or overshoes and this constitutes an important field of use, although the invention is not limited to the manufacture of this or any particular class of footwear.

The machine of my invention includes a novel form or support upon which the sole and upper may be located and properly assembled preparatory to lasting the upper by overwiping its margin upon the sole and securing the overwiped margin of the upper permanently in position by the application of adequate pressure. It will be understood that the margin of the upper and the surface of the sole, or either of them, may be coated with an adhesive effective, upon the application of pressure, to maintain the parts of the shoe permanently in lasted relation. As a convenient and effective means of securing the sole in place upon the form, suction openings are provided in the tread face thereof and the sole is held by suction in place within the projecting margin of the upper, which may be placed about the contour of the form and properly adjusted and positioned by the operator with reference to the sole while the latter is thus held in place. Preferably, movable means, such as a counter clamp, are provided for holding the upper in adjusted position and such means are arranged to be rendered effective by the operator preliminarily to the power operation of the machine.

The machine herein shown as an embodiment of my invention is adapted to the manufacture of footwear characterized by a concave shank and a heel portion of substantial height formed by the upper and the sole, necessitating a heel breast surface of substantial dimensions on the sole extending at an angle to other portions of the sole. To this end, the shank and heel breast portions of the form are of a yieldable character and may be distorted or expanded for the purpose of yieldingly following the sole and upper material supported thereby and applying fluid pressure thereto accurately and uniformly to press the sole against the margin of the upper, whatever the thickness of the materials may be. A novel feature of the invention is to be recognized in fluid pressure means arranged to

act on the inner face of the sole to press the sole against the overlaid margin of the upper.

Another important feature of the invention consists in a form having a defined heel-seat area, a concave shank and an intermediate angularly-disposed heel breast portion, together with means for accurately conforming a flexible sole to the aforesaid contour thereof and holding the conformed sole in place while the margin of the upper is overlaid thereon. A machine of this construction presents the important advantage that the lasting operation may be effected from the heel-seat to the ball line of the shoe in the consecutive steps of a single operation carried out upon a sole and upper brought once for all into proper relation. In the machine herein shown, the heel-seat portion is overwiped, the sole is conformed to the heel breast and shank portions of the form, and the shank portions of the upper are overwiped, all as consecutive and related steps, the lasting steps progressing from the heel-seat and supplementing each other as the upper material is overwiped and secured in place.

My invention further includes as one feature a clamping device or pad arranged to be automatically positioned for holding the upper in place adjacent to the shank of the shoe after the heel-seat has been formed and preparatory to further overwiping of the upper. The pad is arranged to be mechanically actuated and controlled by the operator so that it is brought into action at a point in the cycle of the machine affording opportunity for the proper adjustment of the upper preparatory to overwiping the same along the sides of the shoe in advance of the heel-seat.

The machine of my invention also includes heel-seat wipers arranged to be mechanically operated for overwiping the margin of the upper about the heel-seat and serving also to exert the pressure upon the heel-seat desirable to insure the adhesive union of the upper and sole. The machine shown includes also a shank forming member arranged to be mechanically operated after the heel-seat has been completed to conform the sole to the heel breast portion and the concave shank portion of the form. Means are provided for moving the shank former into place in a path adjacent to the position occupied by the heel-seat wipers at the conclusion of the heel-seat forming operation and for maintaining the shank former securely in place during the ensuing steps of the machine cycle. This combination and mode of operation is believed to be novel and of particular advantage in the manufacture of

footwear in which the upper and sole are fastened by an adhesive.

In still another aspect my invention comprises mechanism operating to form a heel-seat in footwear and to conform a sole to a shank contour therein, in combination with means for lasting the heel breast and shank portions of the upper as subsequent and related operations. There is herein disclosed, however, novel lasting mechanism for use upon the shank portions of footwear which constitutes a feature of my invention capable of general application. In its more specific aspect, the heel breast and shank wiping mechanism shown comprises a pair of wiping devices arranged to be positioned upon opposite sides of the shoe and movable simultaneously toward each other to overwipe the projecting margin of the upper upon the edges of the sole which has previously been conformed to the corresponding surfaces of the form. For reasons of compactness and efficiency, it is desirable to associate the shank wiping devices with the shank former above mentioned and, as herein shown, these may both be mounted on a carrier and brought simultaneously into operative position.

The illustrative embodiment of my invention comprises an organized machine including the numerous mechanisms above discussed, cooperatively related and timed in their operation to carry out progressively the consecutive steps of shaping and fastening by adhesive the sole and upper of footwear from the rear end of the heel-seat, throughout the heel breast and shank portions substantially to the ball line. The cycle of the machine and the mechanism whereby it is carried out possess many features of novelty which will be pointed out in connection with the more specific description of the machine.

These and other features of the invention will be best understood and appreciated from the following description of a preferred embodiment thereof, selected for purposes of illustration and shown in the accompanying drawings, in which

Fig. 1 is a view of the machine in perspective as seen from the right;

Fig. 2 is a view in longitudinal section;

Fig. 3 is a view in side elevation of the machine as seen from the left;

Fig. 4 is a plan view of the wiper mechanism, showing a shoe in operative position;

Fig. 5 is a plan view of the counter clamp mechanism;

Fig. 6 is a view in rear elevation, on an enlarged scale, of the actuating mechanism of the machine;

Fig. 7 is a view in longitudinal section, on an enlarged scale, of the shank forming and lasting mechanism, also showing a shoe in operative position;

Fig. 8 is a view in transverse cross section on the line 8—8 of Fig. 7 but showing the form pad under pressure;

Fig. 9 is a view in perspective of the shank lasting mechanism; and

Fig. 10 is a view in perspective of a shoe as operated upon by the lasting mechanism.

Before proceeding to a detailed description of the illustrated machine, it will be convenient to outline briefly its operating cycle. After the upper has been properly positioned upon the form carried by the jack 50 and the insole located on the bottom of the form and held in place by air suction, the operator depresses the treadle which operates first to bring the counter clamp or band 90 yieldingly into engagement with the back of the upper, thus retaining it against displacement

during the ensuing operations. Continued depression of the treadle thereupon trips the clutch and heel-seat wipers 22 are advanced to wipe the upstanding margin of the upper over the heel-seat of the insole. When the heel-seat wipers 80 are fully advanced, the jack is elevated by power so that the overwiped material and sole are compressed against the under face of the wipers and the machine is brought to rest automatically with its parts in this position.

When the starting treadle is depressed for the second time, the side or shank clamps 150, which have been latched out under tension, are tripped and so permitted to move into engagement with the upper upon opposite sides of the shank. The treadle also operates to swing down the arm 110 carrying transversely-movable shank wipers and a convex form 122 for molding or shaping the insole into conformity with the concave shank face of the shoe form upon the jack. When these two operations have been effected by the movement of the treadle, the clutch is tripped for the second time and the mechanical cycle completed. The arm carrying the shank wipers is first locked rigidly to the frame in position of pressure. The 100 shank wipers are then moved inwardly, overwiping the margin of the upper along both sides of the shank, and a flexible, water-filled section of the shoe form is mechanically caused to bulge or flex so that the overwiped margin of the upper 105 is pressed forcibly into contact with the conformed sole. After an interval, the shank wipers are moved outwardly, the jack lowered to its initial position, releasing the pressure of the shoe bottom against the wipers, the heel wipers are retracted, the counter clamp is also retracted, and the side clamping arms are swung outwardly, thus releasing the lasted shoe upon the form.

With the foregoing outline in mind, the detailed description of the machine may be more readily followed. The head frame 12 comprises two vertically-disposed spaced side members and is supported at a convenient height upon a column 10. The side members of the frame are connected at their upper ends by a flat top plate 14, between which and the top side members is interposed a pair of guide plates 16, each having a guideway formed in its inner edge for the reception of a wiper slide 18. The wiper slide is mounted for movement in a horizontal path from front to rear 120 and carries at its forward end a pair of wiper carriers 20 pivotally supported beneath the slide by a bolt 21 and each shaped to extend transversely across the lower face of the wiper slide 18. A wiper plate 22 is detachably mounted by a bolt 125 23 upon the lower face of each wiper carrier 20, the wiper plates being curved at their inner edges into conformity with the contour of the heel-seat and being so located as to swing in their wiping movement about a point coinciding substantially with the center of the rear edge of the heel-seat of the shoe being operated upon. Each wiper carrier 20 is connected at its rear end by a stud 24 with a slotted link 26 which, in turn, is connected to the top plate by a downwardly-extending bolt 27. The slots in the links 26 permit the wiper slide 18 to be moved from its rearmost position forwardly to bring the wipers 22 adjacent to the sides of the heel-seat of the shoe to be operated upon without imparting transverse movement to the wipers, but when the ends of the slots contact with the bolts 27 the wiper carriers 20 are oscillated with a scissors motion to bring the wipers in, overwiping the marginal edge of the upper material upon the heel- 130

seat. The reverse movement of the wiper slide 18 occurs after the lasted shoe has been lowered out of contact with the wipers 22, and in the final rearward movement of the slide the bolts 27 en-
5 counter the forward ends of the slots in the links 26 and act to swing the wiper carriers outwardly into their initial position. When the wiper slide 18 is advanced and the wipers 22 located in their inner and operative position, the wiper carriers
10 20 are supported against upward pressure by the forward ends of the fixed guide plates 16.

The head frame 12 is provided with bearings for a horizontal cam shaft 40, upon which are mounted cams for operating the wiper slide 18
15 and the other instrumentalities of the machine, to be presently described. The wiper slide 18 is provided on its lower face with a pair of spaced lugs, between which is received the upper end of a cam lever 28 arranged to oscillate upon a
20 transverse shaft 30 disposed parallel to and above the cam shaft 40 and extending between the side members of the frame. The lower arm 32 of the cam lever 28 is provided with a cam roll 34 which runs upon the periphery of a cam disk 36 which
25 is formed integral with a barrel or hub 35 fastened on the shaft 40. A tension spring 33 extends between the arm 32 and a stationary pin set in the machine frame and acts to hold the cam roll 34 always in contact with the contour
30 of its operating cam 36.

The shoe to be operated upon is supported upon a jack 50 pivotally mounted for adjustment by means of a transverse pin 51 which extends between spaced flanges forming a part of the jack carriage 52. The jack carriage is mounted
35 for limited vertical movement in ways formed in a front plate 54 which is bolted to the machine head 12. The body of the jack carriage is provided with a vertical bore threaded at both ends
40 for the reception respectively of a lower threaded plug 55 and an upper threaded plug 56. The rear face of the jack carriage 52 is slotted to admit one arm of a cam lever 59 into the vertical bore and this is engaged between the inner end of
45 the lower threaded plug 55 and a spring bearing member 58 which is yieldingly positioned by a stiff compression spring 57 interposed between the upper side of the bearing piece 58 and the lower end of the threaded plug 56. The cam
50 lever 59 is fulcrumed upon a transverse shaft 60 extending between the side members of the frame 12 and is provided with a cam roller 61 arranged to run upon the periphery of a cam disk 64 pinned to the cam shaft 40. A tension spring 62 serves
55 to maintain the cam roll 61 at all times in engagement with its operating cam. It will be noted that when the cam lever 59 is rocked in a clockwise direction the jack carriage 52 and the parts carried thereby will be yieldingly elevated
60 through the compression spring 57, and when the cam lever 59 is rocked in a reverse direction the jack carriage will be lowered.

Upon the upper end of the jack 50 is detachably secured the form 65 upon which the shoe is to be built. In general contour this conforms to the heel end and shank portions of a last of the size and style of the shoe to be treated and may readily be interchanged for forms of different shape in accordance with the requirements of the work. The upper end of the jack 50 is formed as a rib designed to be embraced by flanges formed integral with the form 65 and the form is locked to the jack by a removable transverse pin 67 which extends through the
75 flanges of the form and the end of the jack.

The form 65, as best shown in Figs. 1 and 2, is provided with an elevated heel-seat portion to which is secured a heel-seat plate 66. The form herein shown is provided with a shank of pronounced concavity, the heel-seat portion of
80 the form having a substantially vertical breast face. The rear portion of the form is provided with vertical air passages 68 which open through the heel-seat plate 66 in segmental suction openings. The passages 68 communicate directly with a transverse passage 69 in the top of the
85

jack 50, a gasket being provided for insuring an air-tight joint. The passage 69, in turn, communicates with a downwardly and forwardly-extending tube 70 which enters the body of the jack 50 and communicates with a vertically-disposed air passage 71 opening through the bottom of the jack. The jack carriage 52 is provided with a downwardly and forwardly-inclined air passage 72 surrounded at its upper end by a gasket. The jack carriage is also provided with a vertical adjusting screw 53 which bears against the lower face of the jack 50 in advance of its fulcrum pin 51. By setting up the adjusting screw 53, the jack 50 is rocked about this pin 100 so as to form a tight seal by means of the gasket between the air passage 71 in the jack and the air passage 72 in the jack carriage. The passage 72 is connected by means of a pipe 73 to an air pump 48 mounted behind the machine frame 12 and driven by a pulley 49 from any suitable source of power. The action of the pump 48 through the connections above described is to create a partial vacuum beneath the heel-seat plate 66 of the form 65 so that an insole placed
105 upon the heel-seat plate will be maintained by suction thereon.

Between the sides of the form 65 and in the shank portion thereof is provided a longitudinally extending recess which stops short of the ends of the sole-supporting face of the form. This recess extends into the breast face of the heel-seat portion of the form beneath the heel-seat plate 66 and is designed for the reception of an elongated hollow flexible fluid container or pad 115 74. This pad is rectangular in cross section, longitudinally curved and provided with an upper concave wall 75 which forms, in effect, the shank and heel breast faces of the form. As best shown in Fig. 7, the pad 74 is provided at its heel-seat end with a clamping bar or filler piece 76 which is attached by a screw to the forward edge of the heel-seat plate 66 and is thus anchored in place thereby. At its forward end the pad is provided with a similar filler piece 77 which is connected by a screw to an end plate and anchored in place by a transverse plate 78 which extends across the form and overlies the recess in which the pad 74 is contained. In its lower face the hollow pad is provided with a filling plug 79 130 135 by which it may be filled with water or oil before being assembled in the form 65. The recess in the form is shaped to receive beneath the pad a head 80 which is recessed to receive the filling plug 79 and to bear upon the pad at both sides 140 thereof. The form 65 and the jack 50 are provided with aligned vertical bores in which is located an operating rod 81 normally out of contact at its upper end with the head 80 but adapted to engage and force the head upwardly at the proper time in the cycle of the machine when the hollow pad 74 is to be flexed. At its lower end the operating rod 81 rests upon an adjustable stop screw 82 projecting upwardly from a cam lever 83 which is mounted to swing about the fulcrum 145 150

pin 51, already mentioned. The cam lever 83 carries a cam roll 84 at its rear end which is arranged to run upon the periphery of a segmental cam 85 bolted to the right-hand face of the cam disk 64, as seen in Fig. 6. As will presently appear, the cam 85 is designed to swing the lever 83 to elevate the operating rod 81 and press on the hollow pad 74, causing it to exert an additional pressure upon the margins of the insole in the shank after the 10 overwiping action of the shank wipers.

The counter clamp mechanism will now be described. This includes a transversely-disposed flexible band 90 which is supported at the forward end of a horizontally moving slide by a pair 15 of side links 91 and a centrally-disposed supporting slide 92, best shown in Fig. 5. The counter clamp slide 93 is forked and provided at its edges with ribs arranged to fit in corresponding guideways in the inner edges of guideway bars 94 which 20 are bolted to the lower face of a flanged web 95, formed integral with the side members of the head frame 12 and located beneath the guide plates 16 for the wiper slide already described. The slide or bar 92 is mounted in an open channel 25 formed in the upper face of the slide 93 and is provided at its forward end with an up-turned ear which is connected by a screw to the center of the clamping band 90. The links 91 are permanently connected to the outer ends of the band 30 and are free to swing transversely upon pivot pins extending upwardly from the slide 93. The result is that when the latter is advanced the band 90 is conformed accurately to the counter part of the form 65, thus clamping and firmly holding 35 the upper material in place thereon. The slide 93 is provided with a downwardly-projecting swivel head 96 which is connected through a substantially horizontal link 97 with the upper end of an arm 98 pinned to the shaft 30 which has already been described as serving as a journal for 40 the wiper slide cam lever 28. At an intermediate point the arm 98 is provided with a swivel head 99, through which extends an operating rod 100. A compression spring 89, interposed between the head 99 and a nut on the end of the rod 100 supplies 45 a yielding connection between the two. At its forward and lower end the operating rod 100 is connected to the upper end of an arm 101 pinned to the inner end of a transverse shaft 102 journalled in a boss projecting outwardly from the left side member of the head frame 12. At its outer end the shaft 102 is pinned to a forwardly-extending arm 103 which has a lost motion connection 50 with the upper end of a treadle rod 105 connected at its lower end to a treadle 106. A tension spring 104 acts normally to elevate the arm 103 and the treadle and to rock the shaft 102 in a counter-clockwise direction. It will be seen that upon depressing the treadle 106 the shaft 55 102 will be rocked in a clockwise direction, as seen in Fig. 3, and through the connecting mechanism above described the slide 93 will be yieldingly advanced and the clamping band 90 brought into operative position about the counter of the shoe being built upon the form 65.

The counter clamping band 90 is maintained in its operative position of pressure so long as the treadle 106 is held depressed. When the heel-seat wipers 22 have made their working stroke and overwiped the margin of the upper about the heel-seat, the counter portion of the upper is, of course, held securely in place upon the form 65 and there is no further necessity for maintaining the clamping band 90 in its forward po-

sition. It will be understood that the treadle 106 must be fully depressed to trip the machine and, consequently, the clamping band is held in its operative position until the working stroke of the heel-seat wipers is substantially completed. The 80 machine is brought to rest automatically with the heel-seat wipers 22 in their inner and forward position, as shown in Figs. 4 and 7, by mechanism which will be presently explained, whether or not the treadle is released. However, in order to restart the machine for the second portion of its cycle, the treadle must be released and the clamping band 90 is, accordingly, retracted by the action of the spring 104 to its initial 85 position, as shown in Fig. 7.

The side or shank clamping devices for the upper will now be described. These comprise a pair of pads 150, each of which includes in its structure a comb plate with upstanding spring fingers 158, as shown in Fig. 3, which are enclosed in a textile envelope. Each comb plate has a downwardly-extending shank mounted to swivel in a boss formed at the upper end of the vertical arm 151 of one of the bell crank levers 151-152. Each of these bell crank levers is 100 mounted to swing about a horizontal stud 153 projecting forwardly from the sides of the machine frame 12. A torsion spring 154 surrounds each stud and tends normally to swing the bell crank levers inwardly, carrying the pads 150 into 105 yielding engagement with the upper upon the form 65 upon opposite sides thereof adjacent to the shank.

The outwardly-extending arm 152 of each bell crank lever is pivotally connected to the upper 110 end of a short vertical link 155. On the right-hand side of the machine the link 155 is connected to the end of the forwardly-extending arm 156 of a cam lever 156-157, which is pinned to the right-hand end of the shaft 60, already referred to. On the left-hand side of the machine the link 155 is connected to a forwardly-extending arm 163 which is pinned to the left-hand end of the same shaft. The rearwardly-extending arm 157 of the cam lever carries a cam roll 115 159 arranged to run upon the periphery of a disk cam 160. The cam 160 is formed integral with a barrel or hub 161 fast upon the main cam shaft 40, being held thereon against endwise movement by a bolt 41. A tension spring 162 120 maintains the cam roll 159 always in engagement with the cam disk 160 and supplements the action of the torsion springs 154 upon the shank clamping mechanism.

In the initial stopped position of the machine, 125 the cam 160 holds the cam lever arm 157 in an elevated position with the spring 162 under tension and the pads 150 in inoperative position spaced away from the form 65, so that the upper may be placed thereon without any interference 130 with the pads. The cam 160 is provided with an abrupt drop-off which releases the cam roll 159 during the first portion of the machine cycle but a latch is provided for preventing corresponding movement of the cam lever 157 at once. The timing of the cam 160 is such that the machine 135 comes to rest at the conclusion of the first portion of its cycle after its drop-off portion has passed beyond the cam roll 159. The cam lever is arranged to be tripped in the depression of the 140 treadle to restart the machine, as will be presently explained, and when this occurs the springs 154 and 162 are effective to move the pads 150 into clamping engagement with the sides of the upper. This occurs during the initial depression 145 150

of the treadle 106 and before the clutch is tripped for restarting the machine for the concluding portion of its cycle. The result is that the upper is yieldingly clamped to the sides of the form 5 adjacent to its shank and the operator is given an opportunity of straightening and adjusting it before the power operation of the machine is resumed.

The mechanism for tripping the shank clamping pads is associated with and forms a part of the mechanism for controlling the position of the overhead arm carrying the shank shaping and lasting mechanism. The latter will, therefore, be described before explaining the tripping mechanism.

A forked and ribbed arm 110 is pivotally mounted at its rear end upon a transverse shaft 111 which extends between ears rearwardly projecting from the upper portion of the head frame 12. Beneath and behind its axis of movement there is secured to the arm 110 an angle bar having a rearwardly extending arm 112 and a forwardly-extending arm 113. The rearwardly-extending arm 112 is connected to a cable 114, from which is suspended a counter weight 115, the cable being guided over a suitable idler pulley mounted in the frame 12. The forwardly-projecting arm 113 acts as a stop to limit the upward swinging movement of the arm 110 by engaging the rear face of the frame 12. The arm 110 carries at its free end the shank forming and wiping mechanism and is normally maintained by the counter weight in an elevated or inoperative position, as shown in Figs. 1 to 3.

The arm 110 is provided with longitudinally-extending ribs at each side and at its free end with a downwardly offset head 118. The design of the arm is such that it may be lowered to a substantially horizontal operative position in which it passes over the top plate 14 and presents the head 118 and the parts carried thereby in position in advance of the heel-seat portion of the form 65. The head 118 is provided with a downwardly-projecting, centrally-disposed slotted rib 119 through which project a pair of parallel, transversely-disposed rods 120. The shank mold or former comprises a vertically-disposed plate 122 shaped at its upper edge to fit into the slot in the rib 119 and having a pair of undercut recesses in its upper edge arranged to interlock with that portion of the rods 120 which extends across the slot of the rib 119. A spring locking pin 123 is mounted in the forward part of the head 118 and arranged to extend downwardly into a socket in the upper edge of the shank former 122 for the purpose of detachably retaining it in position. The shank former 122 is flanged at its lower edge and convex in contour to cooperate with that portion of the concave contour of the form 65 bounded by the shank and heel-seat faces of the latter. It will be understood that other shank formers of different contour may be interchangeably substituted in accordance with the character of the footwear being manufactured.

Two transversely-movable carriers 124 are mounted to slide upon the cross rods 120 and each is provided with a downwardly-extending longitudinal flange 125, to the inner face of which is detachably bolted a side wiping shank mold or wiper 126. The latter are retained in place by clamping bolts 127 which pass through the flanges 125. In contour the wipers 126 correspond to the contour of the shank former 122. In initial position the carriers 124 occupy posi-

tions upon the outer ends of the rods 120, being spaced from each other sufficiently to position the wipers 126 at some distance from the sides of the upper assembled upon the form 65. When the wipers 126 are moved inwardly, in the manner to be presently described, they cooperate with the shank former 122 to cover substantially the whole width of the shank of the shoe, including particularly its outer margin, and in this final position they may be spaced slightly from the opposite sides of the former 122, as shown in Fig. 8.

The shank wipers 126 are actuated by mechanism which will now be described. Each of the carriers 124 is provided with rack teeth 128 in its rear face which mesh with separate pinions 129 fast to the lower ends respectively of a pair of vertical shafts 130 mounted in the rear part of the head 118. Each shaft 130 is provided near its upper end with a second pinion 131 and these pinions are arranged to mesh at opposite sides of a rack slide 132, guided for horizontal movement in ways formed partly in the head 118 and partly in a cover plate 139 secured thereto. The rack slide 132 is adjustably connected by a long screw 133 to a rectangular head 134 movable longitudinally in the arm 110. A fixed stroke is imparted to the head 134 and it will be apparent that the lateral position of the carriers 124 and the limits of its stroke may be adjusted by turning the screw 133 to move the rack slide 132 nearer to or further from the head 134. The head 134 is pivotally connected at its rear end by a cross rod 135 to a link 136 and this, in turn, is connected at its rear end to an upwardly-extending operating lever 142 journaled to swing upon the shaft 111, which constitutes also the axis of movement of the arm 110. A tension spring 140 connected to the arm and acting through the link 136 tends at all times to move the head 134 forwardly in the arm.

The arm is arranged to be positively locked in its lower or operative position by the cross rod 135, which for this purpose is provided at its outer ends with locking heads 137, each of which includes a hardened roller adapted to be drawn rearwardly into engagement with a hook 138 securely bolted to the cover plate 14 upon either side of the arm 110. In other words, after the arm 110 has been lowered to the operative position shown in Figs. 7 to 9 and the head 134 begins to be moved rearwardly in initiating the inward wiping movement of the shank wipers 126, the arm 110 and all the instrumentalities carried thereby are positively locked in operative position by the engagement of the locking heads 137 with the hooks 138. The pressure applied through the sole to the head 118 is thus resisted by this positive and efficient connection and depends in no way upon the strength or accuracy of the mechanism utilized for swinging the arm 110 into its operative position.

The lever 142 which has been referred to as journaled upon the shaft 111 is extended downwardly in the form of a laterally offset arm 143 and this, in turn, is pivotally connected to a forwardly-extending rod 144 which passes through the upper end of a cam lever 146 journaled upon the shaft 30, as shown in Fig. 6, and provided at its lower end with a cam roller 147 arranged to run on the periphery of a cam disk 148 pinned to the cam shaft 40. At its forward end the rod 144 carries an adjustable stop sleeve 145. The cam roller 147 is maintained in engagement at all times with the periphery of its

cam 148 by a tension spring 141. When the arm 110 occupies its elevated position, as shown in Fig. 2, the stop sleeve 145 is spaced a substantial distance from the upper end of the cam lever 146 and the lost motion thus permitted allows the arm 110 to be swung to and from its operative position without obstruction. When the arm 110 is lowered into its operative position, the inner end of the stop sleeve 145 is brought into substantial engagement with the upper end of the cam lever 146 so that when the latter is rocked by its cam it is at once effective to rock the lever 142 rearwardly, locking the head 118 in position and operating the shank wipers. 15 Upon the outer right-hand end of the shaft 111 is mounted a rocker member having a forwardly-extending arm 166 and a rearwardly-extending arm 167. The rearwardly-extending arm is provided with a hub in which is journaled a short horizontal shaft 168. Fast to the right-hand end of this shaft is a dog 169 having a recess adapted in one position of the dog to engage a lug 116 projecting transversely from the arm 110 at a point above its axis of movement. 20 Upon the inner end of the shaft 168 is provided an upstanding arm 170 which stands in the path of an adjustable contact bolt or stud 38 threaded into the rear face of the wiper slide 18. The arrangement is such that when the wiper slide occupies its initial and rearmost position the dog 169, through the arm 170, is positively held from engaging the lug 116 on the arm 110 so that the oscillation of the rocker member 166-167 takes place idly so far as the arm 110 is concerned. 25 On the other hand, when the wiper slide 18 occupies its forward position, as it does at the conclusion of the first portion of the cycle of the machine, the arm 170 is permitted to move forwardly to such an extent that the dog 169 will engage the lug 116 and swing the arm 110 into its operative position. 30

There are two operating connections to the arm 166 of the rocker member. The first is a treadle rod 178 which is hooked over a pin projecting inwardly from the free end of the arm 166 and extends downwardly to the treadle 106. Accordingly, the rocker member is oscillated each time the starting treadle is depressed. In the depression of the treadle for initiating the cycle of the machine, the oscillation of the rocker member is idle since the dog 169 is then maintained in its inoperative position and the cam lever 157 is held against oscillation by its cam 160. 35

The second operating connection to the arm 166 is power operated and comprises a vertically-disposed rod 180 which extends at its lower end into a sleeve or barrel 181, being connected thereto through an adjusting screw 182 threaded into the upper end of the barrel 181 and arranged to be locked in adjusted position by a check nut. At its lower end, the barrel 181 is pivotally connected to the rear end of a cam lever 183 journaled to swing freely upon the shaft 60 and provided at an intermediate point with a cam roll 184. The cam roll is arranged to run upon the periphery of a cam disk 185 which is formed integral with the hub 161 and the side clamp controlling cam 160. A tension spring serves to maintain the cam roll 184 at all times in contact with the periphery of the cam disk 185 and the timing of the cam is such that the rocker member 166-167 is oscillated early in the second portion of the machine cycle to swing the arm 110 by power into its shank-conforming or operative position. The full throw of the cam is

imparted to the rocker member and, consequently, to the arm 110 before the locking rod 135 is displaced rearwardly, and thus positive assurance is had that the arm 110 shall be properly located in operative position before the locking heads 137 engage the stationary hooks 138. 80

The arm 166 of the rocker member is connected through a downwardly-extending link 172 to the forward end of a second rocker member 173 pivotally mounted upon the outer end of the shaft 30 and provided at its rear end with a tooth 174. The tooth 174 of the rocker is designed to engage an angular tail or extension 175 upon the free end of the cam lever 157 when the latter occupies its initial or elevated position and to prevent the cam roll 159 from following the drop-off portion of its cam 160 when the latter is rotated in the initial portion of the machine cycle. A tension spring 176 connected to the forward end of the rocker 173 tends always to maintain it in locking engagement with the cam lever and acts in opposition to the thrust of the link 172 when the rocker 166-167 is moved in a counter-clockwise direction. As will be apparent from the foregoing description, the 85 oscillation of the rocker 173, when the treadle 106 is depressed in initiating the operation of the machine, is merely idle since the cam 160 does not permit movement of the cam lever. Under these circumstances, the tooth 174 is disengaged when the treadle is depressed and re-engaged when the treadle is released. However, when the treadle 106 is depressed for restarting the machine in the second part of its cycle, the cam 160 has rotated to a position in which 90 the cam lever 157 is free to move and, consequently, in this depression of the treadle the cam lever is tripped and the side clamps 150 permitted to engage the upper on the form 65. Continued rotation of the cam 160 returns the side 95 clamps to initial position and brings the cam lever 157 back to its latching position at the conclusion of the machine cycle. 100

The main shaft 40 of the machine may be driven from any convenient source of power and is 105 herein shown as provided upon its left-hand end with a roller or Horton clutch of which the driving member includes a sprocket wheel 190. As best shown in the rear view of the machine of Fig. 6, the sprocket wheel 190 is permanently secured to a rotary driving member 191 journaled to turn freely upon the shaft 40 and recessed at its outer end to receive the driven member 192 of the clutch which is pinned to the outer end of the shaft 40. Between the driving member 191 and the driven member 192 is interposed a roller cage 193 containing a plurality of clutch rollers which are received in tapering recesses formed between the opposed faces of the driving and driven members. When the roller cage is 110 moved to locate the rollers in the wide or deep ends of its recesses, the clutch is disengaged and the driving member runs freely. The roller cage is maintained in this position by a tripping lever 196 having a hooked end adapted to engage one or the other of two teeth 194 and 195 projecting from the periphery of the roller cage 193. When the tripping lever is elevated to disengage one of the teeth of the roller cage, the latter is at once turned to move the rollers into the narrow 115 or shallow ends of their recesses, thus establishing a driving connection between the driving and driven elements of the clutch and setting the shaft 40 in rotation. The roller cage 193 is urged always toward clutch-engaging position by a ten- 120

sion spring which is contained in a circumferentially extending recess in one side face of the cage, as shown in dotted lines in Fig. 3.

The clutch tripping lever 196 is pivotally mounted on the left side of the machine frame and urged at all times into engaging position by a tension spring 197 secured to its forward end. The lever 196 is lifted by a hooked latch piece 198 pivotally connected to the rear end of the arm 103 and arranged to engage a pin 199 on the lever 196 when the arm 103 is rocked in a clockwise direction by the depression of the treadle 106. The latch piece is extended downwardly beyond the end of the driven member 192 and the latter is provided with a pair of diametrically located pins 201 which are designed to contact with the end of the latch piece 198 when the machine is set in operation and to disengage it from the pin 199 of the tripping lever 196. This is a well known expedient for restoring the clutch tripping lever to operative position as soon as the driven shaft has once been set in motion. A pawl 200 is pivotally mounted upon the side of the tripping lever 196 and designed to prevent reverse slipping of the roller cage by engaging teeth in the periphery thereof.

The sprocket wheel 190 is driven through a sprocket chain 202 from a driving sprocket 203 upon the outer end of the shaft of a reducing gear unit 204 which is mounted on a bracket projecting rearwardly from the machine frame and belted to a motor 205 carried by a bracket secured to the base of the machine. The driven shaft of the gear reducing unit 204 is provided with a pulley 206 from which the air pump 48 is driven by a suitable belt.

The machine herein described may be employed with advantage in the manufacture of various types of footwear, and in order to make its manner of operation clear this will be outlined in connection with footwear of the gaiter or overshoe type such as is shown in Fig. 10 of the drawings. This shoe comprises a flexible sole 210 reduced in thickness about its margin and thus provided with a feather 211, which it is customary to coat with an adhesive cement before presenting to the machine. The upper 214 herein shown is of rubberized fabric and is similarly provided with a band of cement 215 about its margin. In Fig. 10 the shoe is represented as having been operated upon by the machine of the present invention and in this process the sole 210 is shaped to present a flat heel-seat 216 merging into a substantially vertical breast portion 217 and a concave shank portion 218. The margin of the upper 214 is overwiped about the heel-seat 216 of the sole, overwiped upon the heel breast portion 217 of the sole and overwiped upon the concave shank portion 218 of the sole. The overwiped margin is subjected to pressure so that the upper and sole are permanently united from the rear of the heel-seat to substantially the ball line of the shoe.

The construction of the machine and the manner of its operation will be more clearly understood from a summary of the successive steps carried out in producing the partially finished shoe shown in Fig. 10. The cemented sole 210 is first placed by the operator upon the upper face of the form 65, where it is immediately securely held by suction of the openings 68 in the heel-seat plate. The upper 214 is next placed about the form 65 with its cemented margin projecting above the heel-seat of the sole and the back seam is straightened. The operator thereupon depresses the treadle 106 and in the initial part

of its movement the counter clamping band 90 is brought into clamping engagement with the rear of the upper, preventing displacement thereof. In this movement of the treadle, the rocker member 166-167 is also oscillated but in this instance its motion is entirely idle. In the continued depression of the treadle, the clutch is tripped and the cam shaft 40 set in operation, whereupon the heel-seat wipers are advanced and the heel-seat lasting operation completed. In the concluding portion of this part of the cycle, the cam 64 operates to elevate the jack, thereby subjecting the overwiped and cemented material to mechanical pressure sufficient to insure permanent adhesion thereof. The starting treadle is then released, whereupon the counter clamping band 90 is retracted although the heel-seat wipers remain in their forward position with the work held under pressure. The machine is automatically stopped by the engagement of the tooth 195 by the tripping lever 196.

The treadle is now depressed to restart the machine and in its initial movement the counter clamping band is again brought into operative position, although its clamping action on the upper is unnecessary at this stage of manufacture. Also, in the initial movement of the treadle the rocker member 166-167 is moved and with it the rocker member 173, so that the cam lever 157 is tripped and the side clamping pads 150 105 are permitted to swing into clamping engagement with the upper along the sides of the shank. The operator is thus afforded an opportunity to adjust and straighten the upper before proceeding with the depression of the treadle which initiates the second portion of the machine cycle. As the treadle continues to be depressed, however, the clutch is tripped for the second time and the rotation of the shaft 40 is continued. When the machine is restarted, the cam 185 at 115 once acts through the connections described to rock the rocker member 166-167 in a clockwise direction, and since the wiper slide has carried the stop screw 38 forwardly, the dog 169 is now in position to engage the lug 116, swinging the arm 110 downwardly and causing the convex shank former 122 to mold or shape the sole 210 into the concave shank portion of the form 65 and into conformity with the vertical face of the heel breast portion thereof. As soon as the arm 123 110 has reached this position, the cam 148 acts to move the head 134 rearwardly, bringing the locking heads 137 into locking engagement with the stationary hooks 138 and thus rigidly locking the arm 110 in its position of pressure. Continued action of the cam 148 and rearward movement of the head 134 and the rack slide 132 causes the shank wipers 126 to move inwardly from opposite sides of the shank and to wipe the cemented margins of the upper over the molded shank of the sole 210. When this second overwiping operation has been fully completed, the cam 85 acts upon the cam lever 83 to elevate the rod 81 and press on the hollow pad 74, thus causing the overwiped margin of the upper to be forced by hydraulic pressure against the operative faces of the shank wipers. In this way, complete contact under powerful pressure is insured of the entire overwiped margin of the upper and the sole throughout the heel breast and the shank portions of the shoe. It will be noted particularly that the pressure to which the hollow pad 74 is subjected is effective in causing the pad to bulge throughout its entire upper and heel breast surface, imparting full pressure to the sole in these locations.

As the shaft 40 continues to rotate, the cam 160 swings the cam lever 157 reversely, separating the shank clamping pads 150 from the work. The cam 64 then becomes effective to lower the 5 jack and release the pressure against the heel wipers. Thereupon, the cam 148 becomes effective to permit forward movement of the rack slide 132, unlocking the arm 110 and outwardly moving the side wipers. The pressure upon the pad 10 74 has meanwhile been released, and finally the arm 110 is permitted to return to its elevated position and the machine is automatically stopped in its initial position, leaving the partially finished shoe free to be removed from the form 15 65. After the shoe has thus been operated upon it is contemplated that the forepart portion of the upper will preferably be shaped and fastened to the sole by the use of a machine shown in my copending application, Serial No. 634,317, filed 20 on Sept. 22, 1932.

The machine herein shown is equipped, as described, with wiper plates for overwiping the margin of the upper upon the sole and while this is the preferred manner of shaping the upper, 25 other or different mechanism, depending on the nature of the footwear, may be employed, it being essential to the invention only that the margin of the upper be laid inwardly over the edge of the sole in position to be secured thereto.

30 While I have illustrated herein only footwear of the gaiter type, it is to be understood that my invention may be advantageously embodied in machines for use in the manufacture of cement lasted shoes of all types or compo shoes, or 35 others in which an adhesive is employed in the shoe bottom as a temporary or permanent securing medium.

Having thus described my invention, what I 40 claim as new and desire to secure by Letters Patent is:

1. In a machine of the class described, a shoe-supporting form having a flat end portion and a concave shank portion, means for holding one 45 end of a sole by suction upon the flat portion of the form, and means for conforming the shank of the sole to said concave portion while so held at one end.

2. In a machine of the class described, a shoe-supporting form having a flat heel-seat portion 50 and a concave shank portion, a suction opening in said flat portion for holding the heel end of a sole thereon, and a convex former movable into the recess of said concave shank portion to conform the shank of the sole to the contour of the 55 form while its heel end is so held.

3. In a machine of the class described, a shoe-supporting form having an elevated heel-seat portion merging through a substantially vertical wall into a concave shank portion, the heel-seat 60 portion being provided with suction openings for holding the heel end of a sole thereon, and a convex former movable toward the shoe-supporting form to conform the sole to said vertical wall and said concave shank portion.

65 4. In a machine of the class described, a shoe-supporting form having an elevated heel-seat portion equipped with means for holding thereon by suction the heel end of a sole, the form having a concave shank section of yieldable 70 character, means for conforming the shank portion of a sole to the concave section of the form while the heel end of the sole is so held, and means for bulging said section to press the sole edges in the shank.

75 5. In a machine of the class described, a shoe-

supporting form having suction holding means at its rear end and an intermediate section of yieldable character, a rigid former movable toward said intermediate section to conform a sole to the contour thereof, and means for bulging 80 said section while the former is held in operative position upon the sole.

6. In a machine of the class described, a shoe-supporting form having a heel-seat plate equipped with a suction opening, a yieldable section 85 in said form including a concave shank portion and a heel breast portion limited by said heel-seat plate, and a shank form movable past the breast edge of said heel-seat plate to conform a sole to said yieldable section while the sole is 90 held at its rear end by suction upon the heel-seat plate.

7. In a machine of the class described, a shoe-supporting form having a heel-seat plate with a suction opening near its rear end and an air passage 95 communicating therewith and a yieldable fluid container having a curved wall which serves as the shank portion of the form.

8. In a machine of the class described, a shoe-supporting form having a heel-seat plate with a suction opening therein and an air passage leading thereto, and an elongated yieldable fluid container having a curved wall which constitutes the shank portion of the form and is anchored 100 at one end beneath said heel-seat plate.

9. In a machine of the class described, a shoe-supporting form having a heel-seat face and having a recess adjacent to said face, an elongated flexible fluid container mounted in said recess and having a concave wall which provides the 110 shank face of the form, means for anchoring said container at opposite ends, and mechanism for flexing said container.

10. In a machine of the class described, a shoe-supporting form having a heel-seat face and a 115 hollow pad arranged to form a part of the contour of the form in advance of its heel-seat face, and a pad-flexing head contained within said form in contact with an inner wall of said pad.

11. In a machine of the class described, a form 120 for building footwear, having a longitudinally extending recess in its sole-supporting face stopping short of the ends of said face, and an elongated hollow flexible pad anchored in said recess and having a wall permanently curved 125 lengthwise of the form to provide a concave shank surface on the form, said pad having a quantity of liquid permanently inclosed within it for transmitting pressure from one portion of the pad to another portion.

12. In a machine of the class described, a form 130 for building footwear, having a recess in its sole-supporting face, and an elongated hollow pad in said recess longitudinally curved and having a wall shaped to provide a concave shank surface 125 and a heel breast surface on the form.

13. In a machine of the class described, a shoe-supporting form having means for holding a portion of a sole in position upon its sole-engaging face and against lateral displacement thereon 140 and within the projecting margin of an upper placed about the form, means for overwiping the margin of the upper while the sole is thus held, and means acting thereafter to conform an unsecured portion of the sole to the form.

14. In a machine of the class described, a shoe-supporting form having means for holding a portion of a sole in position upon its sole-engaging face and against lateral displacement thereon and within the projecting margin of an upper 145 150

- placed about the form, means for overlaying the margin of the upper about the heel-seat while the sole is thus held, means acting thereafter to conform the shank portion of the sole to the 5 surface of the form, and means for overlaying the margin of the upper upon the conformed shank of the sole. 15. In a machine of the class described, a shoe-supporting form having a suction plate in its 10 sole-engaging face for holding a portion of a sole against lateral displacement thereon and within the projecting margin of an upper placed about the form, means for overwiping the margin of the upper about one end of the shoe while the 15 sole is thus held, means for conforming an intermediate portion of the sole to the surface of the form, and means for simultaneously overwiping the margins of the upper from opposite sides upon said conformed portion of the sole. 20 16. In a machine of the class described, a shoe-supporting form having a concave shank and a heel-seat plate provided with a suction opening for holding a sole thereon and within the projecting margin of an upper supported by the form, 25 means for clamping the upper to the form about the counter portion thereof, and means acting while the upper and sole are so held and clamped for overwiping the margin of the upper about the heel-seat. 30 17. In a machine of the class described, a shoe-supporting form having a concave shank and a heel-seat plate provided with a suction opening for holding the heel-end of a sole thereon and within the projecting margin of an upper placed about the form, means movable preliminarily to clamp the upper to the form about the counter portion thereof, means acting while the upper and sole are so held and clamped for overwiping the margin of the upper about the 35 heel-seat, and means acting thereafter for overwiping the margin of the upper at both sides of the shank. 40 18. In a machine of the class described, a form for supporting a sole and an upper to be lasted thereto, mechanism for cement-lasting the heel-seat and holding it compressed, and mechanism for thereafter cement-lasting the shank portion of the upper in advance of the heel-seat while the latter is maintained under 45 pressure. 50 19. In a machine of the class described, a shoe-supporting form having provision for holding a sole thereon and within the projecting margin of an upper placed about the form, means for successively wiping into adhering relation with the sole first the heel-seat portion of the upper and then the shank portion thereof, and means for subjecting said overwiped upper and sole to pressure. 55 60 20. In a machine of the class described, a form for supporting a sole and an upper to be lasted thereto, mechanism for cement-lasting the heel-seat and holding it under pressure, means for conforming the shank of the sole to the form while the heel-seat is so held, and means for thereafter cement-lasting the upper to the conformed shank. 70 21. In a machine of the class described, means for supporting an upper and sole in lasting relation, power-operated wipers for wiping the margin of the upper into adhering relation with the sole about the heel-seat and for holding the overwiped upper and sole under pressure, and means 75 for overwiping the shank portion of the upper while the heel-seat remains undisturbed under pressure. 22. In a machine of the class described, means for supporting an upper and sole in lasting relation, power-operated wipers for wiping the margin of the upper into adhering relation with the sole about the heel-seat, mechanism for moving the supporting means relatively to the wipers for pressing the interposed material, and power-operated shank wipers movable inwardly to overwipe the shank portion of the upper while such pressure is maintained and outwardly after such pressure is released. 80 85 23. In a machine of the class described, means for supporting an upper and sole in lasting relation, power-operated wipers for wiping the margin of the upper into adhering relation with the sole about the heel-seat, mechanism for moving the supporting means to press the interposed material of the heel-seat against the wipers, and shank wipers arranged to overwipe the shank portion of the upper while pressure is maintained on the heel-seat, the supporting means being movable to release pressure thereafter upon both the heel-seat and shank. 90 95 24. In a machine of the class described, a shoe-supporting form having provision for holding a sole thereon and within the projecting margin of an upper placed about the form, means for wiping the heel-seat portion of the upper into adhering relation with the end of the sole, a shank former operating to shape the shank of the sole, means for thereafter overwiping the margin of the upper in the shank, and means for subjecting the sole and the entire overwiped margin to pressure. 100 105 25. In a machine of the class described, a shoe-supporting form having provision for holding a sole thereon and within the projecting margin of an upper placed about the form, means for forming the heel-seat, a shank former movable thereafter to press the sole along a central zone into conformity with the surface of the form, and shank wipers arranged to move inwardly to wipe the margin of the upper toward said former while the shank portion of the sole is thus conformed. 110 115 26. In a machine of the class described, a support for a sole and upper to be lasted thereon, power-operated heel-seat wipers for overwiping the margin of the upper about the heel-seat, means operating thereafter to compress the overwiped heel-seat, shank wipers for overwiping the margin of the upper along the shank, and means acting thereafter to compress the overwiped shank. 120 125 27. In a machine of the class described, a support for a sole and an upper to be lasted thereon, power-operated heel-seat wipers for overwiping the margin of the upper about the heel-seat, means operating thereafter to compress the overwiped heel-seat, shank wipers for overwiping the margin of the upper along the shank upon both sides, and means acting to compress and then release the overwiped shank while pressure is maintained upon the heel-seat. 130 135 28. In a machine of the class described, a support having a flat heel-seat, an angularly-disposed breast portion and a concave shank, heel-seat wipers for overwiping the margin of an upper placed about the support to form a heel-seat and to maintain the same under pressure, means for conforming the sole to the breast and shank portions of the support, power-operated means for overwiping the margin of the upper at the sides of the breast and shank, and means 140 145 150

- for thereupon subjecting the overwiped breast part of the shoe to pressure.
29. In a machine of the class described, a support for a sole and an upper to be lasted thereon, separate counter clamping and shank clamping devices for the upper, power-operated heel-seat and shank wipers, and treadle mechanism for throwing the wipers into action designed to render the counter clamping device and the shank clamping device operative at different points in the cycle of the machine. 80
30. In a machine of the class described, a support for a sole and an upper to be lasted thereon, separate counter clamping and shank clamping devices for the upper, a power driven shaft, heel-seat wipers, shank wipers and treadle-operated mechanism for operatively connecting first the heel-seat wipers and then the shank wipers to said shaft, said mechanism being arranged to render the counter clamping device effective prior to the heel-seat wiping operation and to render the shank clamping device operative prior to the shank wiping operation. 85
31. In a machine of the class described, a support for a sole and an upper to be lasted thereon, power-operated wiping mechanism, and a pair of clamping pads mounted to swing in a vertical plane at right angles to the axis of the sole and arranged to be automatically moved into engagement with the upper upon opposite sides of the shank preliminarily to the operation of the wiping mechanism and thus frictionally to engage the upper while permitting adjustment thereof by the operator. 90
32. In a machine of the class described, a support for a sole and an upper to be lasted thereon, power-operated wiping mechanism, a pair of clamping pads arranged to be latched under tension in positions spaced from the opposite sides of the upper adjacent to the shank portion thereof, and a treadle having connections for throwing the wiping mechanism into operation arranged to trip said pads in its initial movement. 100
33. In a machine of the class described, a support for a sole and an upper to be lasted thereon, power-operated wiping mechanism, and a pair of clamping pads arranged to be latched under tension in positions spaced from the sides of the upper, a cam for setting said pads in initial position and for governing the time of their release, and a treadle having connections for throwing the wiping mechanism into operation arranged also to trip said pads. 115
34. In a machine of the class described, a support for a sole and the upper to be lasted thereon, heel-seat wipers, shank wipers, power actuating mechanism therefor, treadle mechanism operative to throw first the heel-seat wipers and then the shank wipers into action, an upper clamping pad arranged to be latched under tension in a position spaced from the upper, and a cam for setting said pad in its initial position designed to prevent movement of the pad until the time when the treadle mechanism is operated to throw the shank wipers into operation. 120
35. In a machine of the class described, a support for a sole and an upper to be lasted thereon, mechanism for overwiping the margin of the upper completely to form the heel-seat and to hold the same under pressure, power actuated wipers operating thereafter to overwipe the margin of the upper in the shank, and an upper clamping pad mechanically actuated to engage the upper adjacent to the shank prior to the operation of said shank wipers. 125
36. In a machine of the class described, a support for a sole and the upper to be lasted thereon, wiping devices, a spring actuated arm pivotally mounted adjacent to the support and equipped with an upper clamping pad, cam mechanism connected to the arm for retracting the same, a latch arranged to latch the arm in its retracted position, and treadle mechanism arranged to set the cam in operation and also to trip the arm after the cam has moved to releasing position. 130
37. In a machine of the class described, a support for a sole and the upper to be lasted thereon, means for overwiping the margin of the upper about the heel-seat, a carrier having shank wiping devices thereon movable thereafter from an initial position remote from the support to locate the shank wiping devices in wiping position, and means for locking the carrier in such position preparatory to the shank wiping operation. 135
38. In a machine of the class described, a support for a sole and the upper to be lasted thereon, means for overwiping the margin of the upper about the heel-seat, a carrier arm mounted to swing toward and from the support and having oppositely-movable shank wipers mounted at its free end, means for moving said arm to locate the wipers in operative relation to the upper, means for locking the arm against releasing movement, and means for simultaneously actuating the wipers. 140
39. In a machine of the class described, a support for a sole and upper, heel-seat wiping mechanism, a movable carrier having a shank former and a pair of initially spaced shank wipers, means for locating and locking the carrier in operative position, and power actuating means for effecting wiping and retracting movement of the shank wipers while the carrier is thus locked. 145
40. In a machine of the class described, a support for a sole and upper, heel-seat wiping mechanism, a movable carrier having a shank former and a pair of initially spaced shank wipers, means for locating the carrier with the former in contact with the sole throughout its shank portion and for locking the carrier in such position, means for moving the shank wipers to overwipe the margin of the upper in the shank, and means for applying pressure to the overwiped margin while the wipers are retained in their overwiping position. 150
41. In a machine of the class described, a support for a sole and upper, a power-operated heel-seat wiper slide, a movable carrier having shank wipers thereon, and power mechanism for actuating the wipers and carrier having operating connections with the carrier arranged to be rendered ineffective while the slide occupies its initial position. 155
42. In a machine of the class described, a support for a sole and upper, wipers operating to cement-last the heel-seat and hold it under pressure, a movable carrier having shank wipers thereon, and power mechanism for actuating first the carrier and then the shank wipers having operating connections arranged to be rendered effective only while the heel-seat wipers occupy their position of pressure. 160
43. In a machine of the class described, a support for a sole and upper, an oscillatory carrier having a shank former thereon arranged to cooperate with said support in shaping the sole, 165

- transversely movable shank wiping devices associated with the shank former, and mechanism for operating said devices having provision for adjusting their effective stroke.
- 5 44. In a machine of the class described, a support for a sole and upper, an oscillatory carrier having a shank former thereon arranged to cooperate with said support in shaping the sole, transversely movable shank wiping devices 80 mounted at the free end of the carrier, operating means for said wiping devices located in the carrier, and locking means for the carrier arranged to be rendered effective by the action of said operating means.
- 10 45. In a machine of the class described, a sole-supporting form having a substantially flat heel-seat portion and a concave shank portion, means for laying the margin of the heel end of an upper over a sole on the form, and means for thereafter bending the shank portion of the sole into the concavity of the shank portion of the form and for laying the margin of the upper over that portion of the sole. 85
- 15 46. In a machine of the class described, a sole-supporting form having a substantially flat heel-seat portion and a concave shank portion, means for laying the margin of the heel end of an upper over a sole on the form, means movable thereafter to bend the shank portion of the sole into the concavity of the shank portion of the form, and devices carried by said bending means for laying the margin of the upper over the shank portion of the sole. 90
- 20 47. In a machine of the class described, a sole-supporting form having a substantially flat heel-seat portion and a concave shank portion, means for laying the margin of the heel end of an upper over a sole on the form, means movable thereafter to bend the shank portion of the sole into the concavity of the shank portion of the form, and wipers carried by said bending means and movable inwardly toward each other after the sole-bending operation to wipe the margin of the upper over the shank portion of the sole. 95
- 25 48. In a machine of the class described, a sole-supporting form having a concave shank portion, means for bending the shank portion of a sole into the concavity of the form, and devices arranged to be positioned by said bending means for thereafter laying the margin of an upper inwardly over the shank portion of the sole. 100
- 30 49. In a machine of the class described, members movable to lay the margin of an upper inwardly over the bottom face of a sole on a form at the opposite sides of the shank portion of the sole, and a support for said members having means for engaging the shank portion of the sole and movable heightwise of the upper to carry the members into proper relation to the sole for laying the upper inwardly over it. 105
- 35 50. In a machine of the class described, means for laying the margin of an upper inwardly over a sole, and fluid-pressure means arranged to act on the inner face of the sole to press the sole against the margin of the upper. 110
- 40 51. In a machine of the class described, means for laying the margin of an upper inwardly over a sole, and a flexible fluid-containing receptacle arranged to engage the inner face of the sole for pressing the sole against the margin of the upper. 115
- 45 52. In a machine of the class described, a sole-supporting form provided with a fluid-containing chamber having a flexible wall opposite the sole, means for laying the margin of an upper inwardly over the sole, and means to cause the fluid in said chamber to apply pressure to the sole through said flexible wall to press the sole against the margin of the upper. 120
- 50 53. In a machine of the class described, a sole-supporting form provided with a closed fluid-containing rubber receptacle opposite the sole, means for laying the margin of an upper inwardly over the sole, and means for applying pressure to said rubber receptacle to cause it to press the sole forcibly against the margin of the upper. 125
